WITNESS:

UNITED STATES PATENT OFFICE.

SAMUEL D. WORK, OF MINERVA, OHIO.

LOCOMOTIVE CYLINDER COCK.

Application filed November 18, 1926. Serial No. 149,259.

This invention relates to locomotive parts, particularly to cylinder cocks, and has for its object the provision of a novel and improved cock so constructed and arranged as 5 to do away with breaking of the valve as occurs with the use of the ordinary type, the construction being further such as to entirely eliminate the cock rods, cylinder and other material used in present day 10 equipment.

Another object of the invention is to provide a cylinder cock which may be mounted closer to the body of the steam cylinder, thereby greatly reducing the danger of its 15 being knocked off.

It is known that the ordinary types of valve and cock possess many disadvantages, one of which is that when a valve of the 20 present type in common use breaks it becomes "cocked" in the body of the device and dirt will be blown on the guides and pistons, destroying lubrication and cutting the guide and piston packing. It is with these facts in view that I have designed the 25 present invention which has the objects above specified and which has the additional advantage that once it is opened it cannot be closed except by air pressure, thus eliminating danger of movement of the locomotive 30 while in a round-house, such movement ordinarily resulting from cylinder cocks becoming accidentally closed.

An additional object is to provide an apparatus of this character which will not only 35 possess the above advantages but which, moreover, will be simple and inexpensive to manufacture and install, positive in action, efficient and durable in service, and will be a general improvement in the art.

With the above and other objects and 40 advantages in view, the invention consists in the details of construction and the arrangement and combination of parts to be herein-after more fully described and claimed, and 45 illustrated in the accompanying drawings, in which:—

Figure 1 is a longitudinal section through the device showing the parts in one position.

Figure 2 is a cross section taken on the 50 line 2—2 of Figure 1.

Figure 3 is a view similar to Figure 1 with the parts in a different position.

Figure 4 is a cross section on the line 4—4 of Figure 2, and

Figure 5 is a detail view.

Referring more particularly to the drawings, the body of the device is designated, generally, by the numeral 1 and includes an upper portion 2 and a lower portion 3 provided at one side with a lateral extension 4. 55 A threaded head 5 closes the member 3, this head having a protuberance or projection 6 of angular shape thereon engageable by a wrench or the like whereby it may be screwed into or out of place. Within the 60 member 2 is a stop 7. The intermediate portion of the member 3 is constricted as indicated at 8 and formed with a bore 9 adapted to communicate with the atmosphere through ports 10. At the lower portion of 70 the bore 9 the constricted portion 8 is formed with relatively small passages 11 which likewise communicate with the atmosphere. At the upper portion of the bore 9 is a valve seat 12, and located within 75 the bore is a slidable valve 13 adapted to coact with and close the seat 12, this valve having a stem portion 14 projecting down through the neck portion 8 of the lower body member 3. At the upper end of the 80 neck portion 8 is an enlargement 15 to which the upper body member or section 2 is secured as by threading. The lower portion 85 of the lower member is somewhat enlarged and is of hollow formation and located therein is a piston 16 carried by a rod or stem 17 which projects within a tubular guide 18 and which is provided with suitable packing rings 19 to prevent leakage at this point. The provision of the piston 16 defines chambers 20 and 21, the former being 90 below and the latter above the piston. The tubular guide 18 forms a stop for limiting upward movement of the piston 16 as will be readily apparent.

The lateral extension 4 is recessed as indicated, the outer end of the recess being closed by a removable head 22 having a projection 23 thereon of angular shape adapted to be engaged by a wrench or the like where- 95 100

by the head may be screwed into or out of position, as the case may be. Located within the recess in the lateral extension 4 are differential pistons 24 and 25 carried by 5 a piston rod 26, these differential pistons defining chambers 27 and 28. Formed in the wall of the extension 4 is a passage 29 which leads into the chamber 21, and communication through this passage is controlled by means of a slide valve 30 carried by the differential piston 24. It should be mentioned, in passing, that the piston rod 26 is of such length that when the differential pistons are at the inward limit of 10 their movement, this piston rod will extend into the chamber 20 and engage beneath the piston 16 therein for the purpose of preventing downward movement thereof. The purpose for this will be hereinafter made 15 apparent.

Communicating with the chamber 28 is a passage 31 formed in the wall of the extension 4 and extending through the outer end thereof, and likewise formed in the wall 25 of the extension is a passage 32 which communicates with the chamber 27 and with a groove 33, the end of this passage where it enters the chamber 20 being covered or uncovered, as the case may be, by means of a 30 slide valve 34 carried by the piston 16. The wall of the extension 4 is also provided with a relatively small passage 35 which extends from the end thereof in the chamber 20.

When the device is properly connected 35 up with a locomotive, the operation is as follows: Air from the main reservoir passes the three-way valve ordinarily provided in the cab of the locomotive and enters the cylinder cock at the connection provided at 40 the passage 35 and is free to flow into the chamber 20, forcing the air piston 16 upwardly so that the stem 17 thereof will engage against the stem portion 14 of the cylinder cock 13 and lift it from its seat. 45 Steam is free to pass from the cylinder to the atmosphere through the valve seat 12, bore 9 and ports 10. Air from the chamber 20 then passes through the passage 32, uncovered by the upward movement of the 50 slide valve 34, and enters the chamber 27, moving the differential pistons 24 and 25 and the stem 26 carrying the same inwardly. When this occurs the stem 26 projects into the chamber 21 beneath the piston 16, thereby holding the cylinder cock or valve 13 off its seat. In order to close the cylinder 55 cock or valve 13, air is admitted through the connection or the passage 31, the air passing into the chamber 28 and forcing the differential piston to the left, carrying therewith the slide valve 30 and piston rod 26 so that air is free to pass from the chamber 28 through the passage 29 into the chamber 21, thereby forcing the air piston 16 downwardly so that the cylinder cock or valve 60

13 may return to its normal position, by gravity or by steam pressure acting on the valve. The air within the chambers 20 and 21 is released therefrom through the same passages and pipe as it enters by the three-way valve provided in the cab of the locomotive.

From the foregoing description and a study of the drawings, it will be readily apparent that I have provided a greatly improved cylinder cock or valve which, after being opened, cannot possibly return to closed position until positive air pressure is supplied for the purpose. Obviously, this will prevent accidental opening of the valve 75 with the resultant disastrous consequences which might occur. Clearly, the number of parts is greatly reduced and the construction thereby simplified and made much 80 cheaper, the device being therefore easy to manufacture and install. The construction is such that the device may be mounted close to the steam cylinders, thereby greatly reducing likelihood of being knocked off as might occur under some circumstances. It 85 is really believed that the construction, operation and advantages will be readily apparent to one skilled in the art without further explanation.

While I have shown and described the 90 preferred embodiment of the invention, it should be understood that I reserve the right to make such changes in the form, construction and arrangement of parts as will not depart from the spirit of the invention or the scope of the subjoined claim.

Having thus described the invention, I claim:

In a locomotive cylinder cock device, a body member formed at one end with a 105 steam inlet and provided at its other end with a chamber, the intermediate portion of the body having a bore therein terminating in a valve seat communicating with the steam inlet portion, the intermediate 110 portion further having steam outlet ports, a longitudinally movable valve within said bore cooperating with said seat, a piston within said chamber having a stem engageable with said valve for unseating the same 115 when the piston moves in one direction, a stop projectable into said chamber to hold said piston against reverse movement, and air pressure operated means for moving said stop, comprising differential pistons slidably mounted at one side of said chamber portion of the body, and mounted upon a piston rod constituting said stop, and air pressure means cooperating with said differential pistons for moving the same and the 120 stop on which they are mounted, said last means comprising a passage communicating with the space defined between the differential pistons and with said chamber at 125 one side of the piston therein, a compressed 130

air inlet through the chamber at the other side of the piston, a compressed air inlet into the space between the differential pistons, a slide valve carried by one differential piston for controlling the flow of air through said first named passage, a passage communicating with the space at the outer end of the chamber within which the differ-

ential pistons operate and communicating with the first named chamber, and a slide valve carried by said first named piston for controlling communication through said last named passage.

In testimony whereof I affix my signature.

SAMUEL D. WORK.
